UNITED STATES PATENT OFFICE.

WILLIAM H. CHURCH, OF CALGARY, ALBERTA, CANADA.

COMBINATION KNIFE AND SCISSORS SHARPENER.

Application filed April 29, 1924. Serial No. 709,694.

To all whom it may concern:

Be it known that I, WILLIAM H. CHURCH, a subject of the King of Great Britain, a resident of the city of Calgary, in the Province of Alberta, Canada, have invented certain new and useful Improvements in Combination Knife and Scissors Sharpeners, of which the following is the specification.

The invention relates to improvements in combination knife and scissors sharpeners and a general object of the invention is to provide a simple, inexpensive and durable article which can be utilized for sharpening knife or scissors blades and which will do such work effectively.

A further object of the invention is to provide a sharpener embodying sets of rotatably mounted sharpening discs which are adjustable, towards and away from each other thereby permitting one to make the cutting edge of the blade being sharpened more or less acute as he desires.

A further object of the invention is to mount the discs of the sets so that they are permitted a lateral rocking movement, thereby enabling them to more efficiently sharpen the blade.

A further object is to provide the sharpener with a pivoted scissors lining plate which will hold the scissors blade at a proper angle to one of the sets of discs and permit of the efficient sharpening of the scissors blades.

With the above more important objects in view the invention consists essentially in the arrangement and construction of parts hereinafter more particularly described, reference being had to the accompanying drawing in which:

Fig. 1 is a side view of the device as it appears when used in sharpening knives.

Fig. 2 is an end view of the device.

Fig. 3 is a plan view.

Fig. 4 is a plan view showing the discs turned laterally, a position which they take when the knife blade is being drawn thereacross.

Fig. 5 is a sectional view at 5-5' Figure 3.

Fig. 6 is an enlarged detailed vertical sectional view at 6-6' Figure 5.

In the drawing like characters of reference indicate corresponding parts in the several figures.

The body or frame 1 of the sharpener comprises a base plate 2 which is provided

at the sides with two similar upstanding and opposing side wings or bearing plates 3 and 4 and also centrally with two outstanding fastening ears 5 and 6. In the present instance, the wings and ears are integrally formed with the base plate 2 and the ears are provided with suitable holes to receive fastening screws 6 and 7 whereby the body can be permanently fastened to an under support such as a table.

The wings carry a stationary elevated cross shaft 8 and a lower pivot pin 9 and on the pivot pin I pivotally mount the lower ends of upstanding, spaced, opposing side arms 10 and 11 which are formed at the inner end of an outwardly extending adjusting arm 12, the adjusting arm overhanging one end of the base plate. The upper ends of the side arms 10 and 11 are forked as indicated at 13 and the forks carry an elevated cross shaft 14 parallel to the shaft 8 and the ends of the former shaft are extended into similar slots 15 formed in the side plates 3 and 4 and arranged concentric to the pivot pin 9. An adjusting screw 16 is screw threaded through the outer end of the adjusting arm 12 and has the lower end thereof engaging the base plate and the upper end provided with a suitable grip 17 such as a winged head. A spring 18 is mounted on the pivot pin and engages the base plate and the adjusting arm and normally presses the adjusting arm downwardly.

According to the above arrangement, it will be apparent that by turning the screw in one direction or the other, I can rock the shaft 14 towards or away from the shaft 8 and the screw will maintain it in any adjusted position.

On each of the shafts 8 and 14 I mount a set of similar sharpening discs 19, the discs being spaced apart a pre-determined distance by inserted washers 20. The discs and washers are loosely mounted on the shafts so that they can rock thereon, and when the discs are placed on the shafts, the set of discs on the shaft 14 are alternated with those on the shaft 8 and the inner edges of the discs lap as best shown in Figure 3. The discs and the washers are also permitted free end play on the shafts and the disc peripheries are sharpened so that they present keen cutting edges. It is also to be observed that the side wings 3 and 4 have the upper portions thereof cut, for the

greater part, more or less concentric to the shafts and their radii somewhat less than the radii of the discs and that between the shafts 8 and 14, clearance pockets 21 are provided on each side and formed in the wings.

The device as hereinbefore described is utilized for sharpening knife blades, the blade being held in a vertical position and 10 being drawn across the acute angled corner 22 appearing between the sets of discs. As the knife blade is pulled endwise and pressed downwardly, the discs will swing laterally and upset slightly, as best shown in Figure 15 4 and the cutting edges of the discs will accordingly obtain a better bite on the knife blade than if they were held in parallelism as is usually done. The cutting edge of the 20 knife blade can be varied by adjusting the screw 16 to swing the discs closer together or farther apart. If a very acute knife edge is desired, the screw will be adjusted to move the sets of discs apart, whereas if a less acute edge is wanted, the discs will be brought 25 closer together. Here it will be observed that as the shaft 14 is moving away from that 8, the cutting corner 22, so to speak, moves down and the biting edges of the discs become more vertical.

In order that scissor blades may be sharpened with this device, I provide a scissors lining plate 23 which is provided with a finger piece 24, two side arms 25 and 26 and a pair of stops 27 and 28 carried by the side 35 arms. The side arms are pivotally mounted on the shaft 8 and the stops 27 and 28 are adapted, when the lining plate is swung upwardly and inwardly, to engage with the pockets and stop the lining plate in a substantially vertical position or as shown in dotted outline in Figures 1 and 5. In this movement, the lining plate swings entirely clear of the discs on the shaft 8 and when it is brought to the vertical position, it overhangs the inner sides of the discs on the shaft 14. When used for sharpening scissors, the lining plate is in the position shown in dotted outline in Figures 1 and 5 and the scissors blade is held in the vertical po- 40 45

sition against the lining plate and drawn 50 over the presented edges of the underlying discs carried by the shaft 14. During this action, care should be taken that the lining plate is held firmly as this will insure a uniform cutting edge on the scissors blade. 55 The angle of intersection, indicated at 29 of the lining plate with the cutting edges of the discs, is the angle of the cutting edge of the scissors blade. In this connection it is also to be noted that the discs on the shaft 60 14 can be adjusted to make the cutting edge of the scissors blade more or less acute in the same manner as is done with a knife blade and in this connection it is to be noted that the scissors blade is only drawn across 65 one set of discs, that is those carried by the shaft 14.

What I claim as my invention is:—

1. In a blade sharpener, a base provided with opposing side wings, a cross shaft carried by the wings, a set of similar spaced sharpening discs rotatably mounted on the shaft, a rocker member carried by the base, a cross shaft shiftable with the rocker member and movable towards or away from the former shaft, means for holding the rocker member in any adjusted position and a plurality of similar suitably spaced sharpening discs carried by the shiftable shaft and alternated with the former disc. 70 75 80

2. In a blade sharpener, a base provided with opposing upstanding side wings, an elevated cross shaft carried by the wings, a plurality of suitably spaced sharpening discs rotatably mounted on the shaft, a pivotally mounted adjusting arm contained between the wings and provided with upstanding opposing side arms, a cross shaft carried by the side arms, a plurality of suitably spaced sharpening discs rotatably mounted 85 90 95 on the latter shaft, the said latter discs being alternated in respect to the former discs and an adjusting screw carried by the adjusting arm and engageable with the base.

Signed at Calgary, Alta., this 14th day 95 of March, 1924.

WILLIAM H. CHURCH.
